UNITED STATES PATENT OFFICE

2,599,855

LOAD-HANDLING ATTACHMENT FOR
LIFT TRUCKS

William W. Michaux, Jr., Richmond, Va.

Application April 17, 1950, Serial No. 156,340

10 Claims. (Cl. 214—66)

1

In the handling of large heavy and bulky articles of generally uniform size and shape such as hogsheads of tobacco or rolls of newsprint, it is customary to use so-called "lift trucks" which are power-operated trucks incorporating hoisting or lifting mechanism. One form of such a lift truck consists of a wheel-supported frame having normally vertical guide means on which a slide including normally horizontal article-supporting arms or forks is mounted. The power means, usually an internal combustion engine carried by the frame, can be connected to elevate the slide along the aforesaid guide means from one position in which the article-supporting forks are closely adjacent the floor, to another position in which these forks are elevated several feet above the floor so that articles of the kind described can be conveniently elevated for transportation from one location to another, for stacking, or other purposes. In the power-operated handling equipment just described, the vertical guide means previously mentioned is mounted upon the frame for pivotal movement or tilting about a horizontal axis close to the floor and normal to the vertical guide surfaces and to the aforesaid forks. In using such equipment, for instance, to elevate hogsheads of tobacco from one level to another, as in stacking, the truck is propelled forwardly until the supporting forks are thrust beneath the hogshead. The hoisting mechanism is then clutched in to elevate the forks and, substantially simultaneously, to pivot the guide means about its horizontal pivot axis whereby the free ends of the forks are tilted upwardly and gravity acts to hold the hogshead from rolling off the forks. After the hogshead has been elevated to the desired height and properly positioned, the guide means is restored to the vertical so that the hogshead either rolls off the now horizontal forks by itself or by the application of a small force applied manually.

In the practice just described, difficulty is frequently encountered in getting the forks fully beneath the hogshead. That is, the hogshead, unless prevented from so doing, may start to roll away from the truck before the forks can be tilted sufficiently to hold it in position thereon. Furthermore the tilting of the guide means or columns together with their forks, is a time-consuming operation amounting to a large loss in the course of handling hundreds or thousands of articles.

It is therefore the principal object of my invention to provide a device in the nature of an attachment for hoisting and handling equipment of the type, described, particularly lift trucks,

2

wherein the objections and drawbacks enumerated are overcome and obviated.

More particularly, it is the purpose of my invention to provide an attachment which as the forks are thrust beneath an object to be moved, automatically operates in response to engagement with the object to positively secure the object on the forks and to prevent it from rolling or sliding thereoff.

10 Another object is the provision of an attachment as described which, by securing the hogshead or other object upon the supporting forks, makes it unnecessary to tilt the guide columns or mast upon which the load carriage is mounted for translation. Indeed, where a lift truck is built solely for handling of articles or objects of the type described, the tilting mechanism may be eliminated with a corresponding substantial reduction in initial cost of the equipment.

15 20 A still further object is the provision of an attachment as described which is relatively simple and inexpensive to construct, positive in operation, and which may be easily applied and attached to existing lift trucks as well as embodied in trucks to be built.

25 30 Another object is to provide a mechanism as described which is positive and automatic in operation in securing in position upon the forks, an object or article being transported and one which is easily and simply released when the object or article is to be deposited.

35 35 Yet another object is to provide a combined lift truck and article-securing attachment therefore which permits the elimination of complicated and expensive parts of the truck while retaining all the functions of prior art lift trucks.

40 Other objects and advantages will be apparent to those skilled in the art after a study of the following detailed description in connection with the accompanying drawings.

45 40 In the drawings:

Figure 1 is a side elevation showing a lift truck equipped with my invention and, in dotted lines, the position of the parts when the truck has been operated to raise a hogshead of tobacco to substantially maximum elevation.

45 50 Figure 2 is a plan view to an enlarged scale of the lift portion of a truck equipped with the invention, the tine or article-engaging part being shown in forward or unlocked position.

55 Figure 3 is a detail sectional view on line 3—3, Figure 2, and to an enlarged scale, of the rearward portion of the support bar and locking slide, the parts being in a position of the tine corresponding to Figure 2.

55 Figure 4 is a view corresponding to Figure 3

but showing the slide bar in position locking the tine in position to secure an article on the lift forks.

Figure 5 is a view corresponding to Figure 4 but showing the end of the locking slide in raised position to unlock the same.

Figure 6 is a side elevation of the support arm and tine, the latter being in locked position, and

Figure 7 is a cross section on the line 7—7 of Figure 3.

Referring in detail to the drawing, and particularly to Figure 1, the numeral 1 identifies generally a well-known type of power operated lift truck comprising a body 2 supported for rolling movement by two-power-driven wheels 3 and a steering wheel 4. The body has a platform 5 on which the operator stands to operate steering wheel 6 and control levers, one of which is indicated at 7. The lift guide or frame comprises generally a pair of spaced generally vertical beams of masts rigidly connected in spaced parallel relation. One of these beams is shown at 8. This frame is pivoted to body 1 for angular movement about a horizontal axis generally coincident with the axis of wheels 3. A power-operated lever 9 is pivoted at one end to the lift frame and is retractable by power-operated mechanism, not shown, to pivot the frame and load-supporting slide 10 about the aforesaid axis from the position shown upon Figure 1 to a position in which the frame 8 is tilted rearwardly a few degrees.

The slide 10 has interconnected elongated slide members, each guided for vertical translation by the channels of frame 8. Such translation is effected by well-known mechanism including chains 11. A pair of lift forks 12 and 13 (see Figures 1 and 2), are fixed to the lower portion of slide 10 in parallel spaced relation to the floor when the slide is in lowermost position. A prime mover, usually an internal combustion engine, is mounted in body 2 and can be connected by suitable control levers such as 7 to propel the truck, elevate the slide 10 and tilt the frame 8.

The mechanism described in the preceding paragraphs is well known and, apart from the combination, forms no part of my invention, now to be described. The load supporting slide 10 has a carriage guard 10a rigidly connected with the slide. To the uppermost horizontal member of this guard, I attach in spaced relation therewith, a pair of brackets 14 and 15, Figure 2, in which a shaft 16 is journaled in horizontal position. A forwardly-extending arm 17 is fixed at one end upon shaft 16 adjacent bracket 14. See Figures 3 and 4. A brace bar 18 is fixed at one end to arm 17 and at its other end to shaft 16 adjacent bracket 15, to impart rigidity to the arm. As shown upon Figure 7, the arm may be rectangular in cross section. By this construction, the arm is mounted for swinging in a vertical plane about the axis of shaft 16, from the generally horizontal position shown at Figure 1, to a vertical position. A bracket 20, is fixed to a portion of the carriage guard 10a, to limit downward pivotal movement of arm 17 to the horizontal position shown.

A tine 21 of the general shape shown in Figure 6, has a longitudinal slot 22 formed in its central portion of a width sufficient to accommodate the end of arm 17 with a smooth fit. A pin 23 passes through the tine and arm to pivotally connect them whereby the tine may pivot from the loading position of Figure 1, to the locking position of Figure 6. Clockwise movement from the loading position is limited by en-

gagement of the corner 22a of the slot with the top surface of arm 17. This limit position is about as shown in Figure 1 in solid lines.

5 A channel locking bar 24 has a sliding fit over the arm 17 and extends therealong from a point somewhat rearwardly of tine 21, as shown in Figure 1, to a point a little forwardly of shaft 16. The forward end of the locking bar has a strap portion 24a extending downwardly and about the arm 17 whereby this end of the bar is limited substantially to sliding movement along the arm. This end of the bar also has an upwardly offset portion 24b. A pair of links 25 and 26 (see Figures 2 and 6) are connected by a common pivot pin 27 with the forward or load-engaging end of tine 21 while another common pivot pin 28 connects these links with portion 24b of bar 24. By this construction, the locking bar is in the forward position of Figure 1 when the tine extends forwardly and in the rearward position of Figure 6 when the tine extends rearwardly in locked position.

20 The rearward end of bar 24 has a strap portion 24c extending downwardly and about arm 17. As seen in Figure 7, there is a substantial clearance between the strap and arm so that the bar, at this end, may be moved upwardly a short distance. This end of channel or bar 24 has a raised or upwardly inclined cam portion 24d and an aperture 29 adapted to drop over pawl 19 fixed with arm 17 as the bar moves into locked position. Thus, as the locking bar slides rearwardly on arm 17 in response to swinging of tine 21 from forward position to locking position, cam portion 24d rides up on pawl 19 and, in the final locking position of tine 21, bar 24 drops over pawl 19 to hold positively or lock the tine in final position.

25 A pair of links 30, one of which is shown at Figures 3, 4 and 5, has spaced apertures. Shaft 16 passes through the lowermost of these apertures and each link is rigidly secured to the shaft as by welding or set screws. A release rod 31 is journaled in the second or upper apertures of links 30 and is fixed against axial movement as by collars. At its portion in alignment with cam portion 24d, rod 31 has a release lug 32 fixed thereto so that when the parts are in the locking position of Figure 4, cam portion 24d lies directly over lug 32. Then when shaft 31 is pivoted clockwise to the position of Figure 5, lug 32 lifts the adjacent end of locking bar 24 until it clears latch 19 to thereby free the tine for movement to forward or article-releasing position. An operating lever 33 is fixed to the left end of rod 31.

30 For operating lever 33 clockwise to release the bar 24 from pawl 19 I have provided a vertical tube 34 positioned at the right of the operator when he is in position upon platform 5. This tube has a pulley 35 fixed at its top. A weight 42 slides within the tube and is connected by a cord or rope 36 with lever 33. As shown at Figure 1, this cord has one end attached to lever 33 and then passes downwardly about a pulley 37 attached to a bracket carried by slide 10, then upwardly over and about a pulley 38 carried at the top of the frame or mast 8 and thence in a horizontal pass to pulley 35. This horizontal pass therefore at all times extends diagonally across and in front of the operator and is always in the same convenient position. As the load-supporting slide 10 is elevated by chains 11 under drive from the motor of the truck, the weight within tube 34 slides therein and acts to keep the cord 36 taut. A second pulley 38a is mounted at the top of the frame just above and closely adjacent

pulley 38. As the slide is elevated and pulley 37 moves above pulley 38, the cord 36 then extends from the horizontal pass under and upwardly about pulley 38a, as indicated in dotted lines upon Figure 1.

For the purpose of resiliently and yieldingly holding the rearward end of bar 24 upon arm 17, a rod 39 is fixed at one end to shaft 31. The other end of this shaft is bent at 90° and has a roller 40 journaled thereon in position to contact the upper surface of bar 24. A tension coil spring 41 is secured at one end to rod 39 and at the other end to the adjacent side of arm 17 and thus acts to urge the roller down upon bar 24 and to yieldingly hold the bar upon arm 17 unless and until released by a pull on cord 36. Spring 41 also acts to hold lever 33 in the inactive position shown upon Figure 1.

In operation, the truck with parts as shown in Figure 1, is propelled toward a hogshead H of tobacco. As the gripping end of tine 21 contacts the upper portion of the hogshead, the tine is pivoted rearwardly while at the same time the arm 17, bar 24 and parts attached thereto, may pivot upwardly slightly about the axis of shaft 16. The parts are so proportioned and dimensioned that forks 12 and 13 are fully positioned beneath the hogshead shortly after the instant that bar 24 drops into locking position over pawl 19. The parts are then substantially as shown in the dotted line position of Figure 1 whereby the hogshead is securely held against rolling off the supporting forks. The lift slide may then be operated to raise the hogshead to the desired or necessary height. When it is desired to release the hogshead, the operator merely reaches up and pulls upon the horizontal pass of cord 36 to pivot lug 32 and thereby effect release of bar 24 in the manner obvious from inspection of Figure 5. Of course, the invention is equally useful when the truck is being used to remove hogsheads from a stack thereof to the floor.

While, for the purpose of complying with the patent statutes, I have described the device in connection with the handling of hogsheads of tobacco, it will be understood that, as already intimated, the invention is not limited to such use but can be readily adapted for handling rolls of newsprint, barrels, kegs, drums and other articles of regular or irregular shape. Hence the foregoing description is to be taken in an illustrative rather than a limiting sense; and it is my desire and intention to reserve all substitutions and modifications falling within the scope of the subjoined claims.

In the claims, the terms "load-release" and "load securing" positions as referred to the tine 21 means the respective positions thereof in which the tine releases and secures a load upon the forks 12 and 13.

Where articles are being handled which might be damaged by the use of a pointed tine as shown, such for example, as rolls of newsprint, a tine equipped with a tip of rubber or other frictional material will be substituted.

Having now fully disclosed the invention, what I claim and desire to secure by Letters Patent is:

1. The combination with the vertically movable slide and load-lifting fork of a lift truck, of a normally horizontal arm carried by said slide above said fork and having a latch at one end, a tine pivoted to said arm at the other end thereof, a bar slidable on said arm, a link pivoted at its ends to said tine and bar, respectively, whereby said bar is translated along said arm in

response to pivoting of said tine, and means on said arm releasably engaging said latch when said tine extends downwardly and rearwardly toward said latch.

5 2. In combination, a vertically movable slide of a lift truck, a load-lifting fork carried by said slide and extending horizontally therefrom a normally horizontal arm pivoted on said slide above and over said fork, said arm having a latch adjacent one end, a tine pivoted to said arm at the other end thereof, a bar carried by said arm, means mounting the end of said bar adjacent said tine for sliding only on and along said arm, a link connecting said end of the bar and tine, 10 whereby said bar slides upon said arm in response to pivoting of said tine, means mounting the other end of said bar for sliding and/or lateral movement relatively to said arm, and means carried by said other end of the bar for cooperation with said latch to automatically lock said bar in position corresponding to a load-securing position of said tine relatively to said arm.

15 3. In combination, a vertically movable power-operated slide for a lift truck, a load-lifting fork carried by said slide, an arm above and extending over said fork in generally parallel, vertically-spaced relation therewith, a tine connected with said arm at one end thereof for movement from a first position releasing a load on said fork 20 to a second position securing a load thereon, bar means carried by said arm and connected with said tine at one end thereof for movement from first to second position relatively to said arm, by and in response to corresponding movement of 25 said tine, and latch means operable automatically as said bar means moves into second position to positively lock said bar means and tine in their 30 second positions.

35 4. In a device to secure a load upon the forks 40 of a lift truck, a shaft, an arm fixed at one end to said shaft at right angles thereto, a load-engaging tine pivoted on said arm at the other end thereof, a bar carried by said arm and substantially coextensive therewith, means mounting the 45 end of said bar adjacent said tine for translation only on and along said arm, link means pivotally connected at one end with said tine and at its other end with the adjacent end of said bar, whereby said bar is slid along said arm from first to second positions in response to movement of said tine on said arm from load-releasing to load-securing positions, respectively, latch means between said arm and bar adjacent said shaft and operable automatically in response to movement 50 of said bar to second position to lock the same in second position, bracket means fixed to said shaft, a rod journaled in said bracket means parallel with said shaft, and latch release means carried by said rod and operated by pivotal movement thereof to release said latch means.

55 5. A device as recited in claim 4, said bar being adapted for lateral movement relatively to said arm at its end adjacent the shaft to release said latch means, and a lug carried by said rod to engage and so laterally move said bar and release said latch in response to pivotal movement of said rod.

60 6. A device as recited in claim 5, a lever fixed to said rod and having one end extending over said bar, and spring means urging said lever into contact with said bar to hold the same in engagement with said arm.

65 7. For use in a lift truck having a vertically movable slide and a normally horizontal elongated arm pivoted at its inner end to said slide

on an axis normal thereto, a tine pivoted to said arm at the outer end thereof, for pivotal movement from a first position extending forwardly and downwardly with respect to said arm, to a second position extending rearwardly and downwardly with respect to said arm, a locking bar pivoted at its outer end to said tine and slideable along said arm in response to movement of said tine between first and second positions, detent means carried by the inner ends of said arm and bar and automatically operable in response to movement of said tine into second position to lock the same in said second position.

8. In a device of the type described, a vertically movable slide of a lift truck having load-supporting fork projecting therefrom, an arm pivoted at one end on said slide above said fork in normally parallel relation therewith, tine means carried by said arm at the other end thereof above said fork and pivotable thereon from a load-releasing to a load-securing position, a bar slideable on and along said arm, link means connecting one end of said bar with said tine for sliding said bar from a first to a second limiting position in response to pivotal movement of said tine from load-releasing to load-securing position, a latch fixed on said arm adjacent the pivot thereof, and means carried by said bar to engage said latch and releasable lock said bar relatively to said arm as the bar moves into second position.

9. The combination with a lift truck having a slide guided for vertical movement and a pair of normally horizontal load-supporting forks fixed to said slide, of an arm carried by said slide in vertically spaced parallel relation with, and above said forks, a tine pivoted to the outer end of said arm and pivotable thereon from a forward and downward release position to a rearward and

5 downward, article-retaining position, a lock bar pivoted at one end to said tine and longitudinally slideable on and along said arm, and means operable automatically to lock said bar to said arm in response to pivotal movement of said tine to release position.

10 10. In combination with a hoisting and handling mechanism having a vertical slide and article-supporting means guided for translation on and along said slide, an arm pivoted on said slide above and in spaced generally parallel relation with the article-supporting means, article-engaging means carried by said arm at the end thereof and movable in response to engagement with an article as it moves onto said article-supporting means, from article-release position to article-locking position, means automatically operable to releasably lock said article-engaging means in locking position, and manually operable means to release said locking means.
